PLATE

Edgar M. Bottome, Moundsville, W. Va., assignor to Fostoria Glass Company, Moundsville, W. Va., a corporation of West Virginia

Application November 26, 1948, Serial No. 149,830

Term of patent 14 years

(Cl. D44—15)

To all whom it may concern:

Be it known that I, Edgar M. Bottome, a citizen of the United States of America, residing at Moundsville, in the county of Marshall and State of West Virginia, have invented a new, original, and ornamental Design for Plate, of which the following is a specification, reference being had to the accompanying drawing, forming a part thereof, wherein:

The single figure of the drawing is a top plan view of a plate, showing my new design.

The essential feature of the design resides in the floral ornamentation as shown, which is understood as repeating around the periphery of the plate.

I claim:

The ornamental design for a plate, as shown and described.

EDGAR M. BOTTOME.
